his Attorney.

UNITED STATES PATENT OFFICE.

WILLIAM D. CARRINGTON, OF INVER GROVE, MINNESOTA.

SIGNAL FLAG.

1,420,967.

Specification of Letters Patent. Patented June 27, 1922.

Application filed May 23, 1921. Serial No. 471,799.

To all whom it may concern:

Be it known that I, WILLIAM D. CARRINGTON, a citizen of the United States, residing at Inver Grove, in the county of Dakota and 5 State of Minnesota, have invented new and useful Improvements in Signal Flags, of which the following is a specification.

The object of my invention is to provide improved signal flags particularly adapted 10 for use on locomotive engines.

More particularly it is my object to provide such flags in combination with a protective housing and means for quickly displaying or furling the signals.

15 Flags, of the class to which my invention relates, are used to identify the character of certain trains and are usually displayed on each side of the front of a locomotive. According to standard practice regular trains 20 running upon schedule time, display no signal; special trains display a white flag and second sections or other trains, running off regular schedule, display a green flag. The flags in common use for this purpose are 25 pieces of bunting of the desired color tacked on a wooden stick and when not in use they are supposed to be carried in the engine cab. The same train is often required to run without displaying this signal during a portion 30 of a trip and then, because of delays or when running over the track of another road, it is necessary to display a signal flag for longer or shorter periods. At the end of a run such flags are frequently lost or mis- 35 laid and often through forgetfulness of the fireman a locomotive leaves the round house without flags. In consequence there is unnecessary loss of flags and not infrequently a delay in starting a train and in 40 some instances absence of flags when they should be displayed.

45 My invention obviates this inefficiency by having suitable casings, containing the flags, constantly upon the locomotive ready for use.

The drawings, forming a part of this specification illustrate what I at present believe to be the best form of my device but it will be readily understood that modifications are possible within the spirit of my invention.

50 Referring to the accompanying drawings Figure 1 is a side elevation of my device showing one of the flags in extended position; Fig. 2 is an enlarged section taken on the line 2-2 of Figure 1 and Fig. 3 is a

section taken on the line 3-3 of Fig. 2, and the flags being shown in furled position.

My device consists generally of a casing 10 adapted to enclose a plurality of flags 60 and arranged to be secured to a locomotive or railway car by means of a standard 11. This standard forms one side of the casing and is perforated at 12 to receive bolts or rivets for securing my improved signal to 65 the rolling stock. One side of the casing 10 is closed by doors 13 and 14 which are pivotally mounted upon rods 15, the ends of said rods being secured in the top and bottom of the casing 10. The door 14 is provided with a pair of eyes 16 near its ends and a similar pair of eyes 17 are rigidly mounted on the casing 10 opposite the eyes 16. Helical springs 18 connect the eyes 16 with the eyes 17 to resiliently hold the door 70 14 in closed position. The door 14 overlaps the door 13 (as clearly shown in Fig. 75 2) so that the springs 18 also operate to hold the door 13 in closed position.

Revolutionally supported at their ends in the 80 top and bottom of the casing 10 is a pair of spindles 19 and 20 which are bent at their upper ends to form cranks 21 and 22. Longitudinal movement of the spindles 19 and 20 is prevented by cotter pins 23 which are 85 inserted in suitable perforations in said spindles near their extremities. The flags proper 24 and 25 are secured at their inner edges to the spindles 19 and 20 by a series of cotter pins 26 and the opposite edges of 90 said flags are free to be extended through the door openings.

In use my device is secured to the locomotive or railway car as described above and when it is unnecessary to display the flags 95 they are rolled upon the spindles 19 and 20 by manipulating the cranks 21 and 22. When thus furled the flags are effectually protected from weather and wear, the doors 13 and 14 being held shut by the springs 100 18. When it is desired to display one of the flags, the door 13 or 14 is opened against the action of the spring 18 and the appropriate flag is withdrawn as shown in Figure 1. When it is desired to change flags the 105 one displayed may be quickly rolled up by manipulating the crank 21 or 22 and the other flag unfurled as described above.

For use on the front of locomotives I provide two of my signals, one with the doors 110 13 and 14 opening to the left and the other with said doors opening to the right so that

the flags are always accessible to be displayed on each side of the train.

Having described my invention what I claim as new and desire to protect by Letters Patent is:

1. In a device of the class described a casing adapted to be secured to a locomotive, a door in said casing, resilient means for normally holding said door in closed position, a spindle revolvably mounted in said casing, a flag secured at one edge to said spindle and arranged to be frictionally engaged by said door when extended and means for turning said spindle to wind said flag thereon.
2. In a device of the class described, a standard, a casing mounted on said standard, a door in said casing, a second door arranged in said casing to over-lap said first mentioned door, resilient means for holding

said second door in closed position, spindles revolvably mounted in said casing, a flag secured at one edge to each of said spindles and means for rotating said spindles to wind said flags thereon.

25

3. In a device of the class described, a standard, an upright casing mounted on said standard, a door in said casing, a second door arranged on said casing to overlap said first mentioned door, springs to hold said second door in closed position, spindles revolvably mounted in the ends of said casing, cranks on one end of each of said spindles, flags secured at one edge to said spindles severally and arranged to be selectively extended through said doors.

30

In testimony whereof, I have hereunto signed my name to this specification.

WILLIAM D. CARRINGTON.
